AWNING STRUCTURE

Joseph D. Stevens, Baltimore, Md.

Application July 25, 1931, Serial No. 553,158

2 Claims. (Cl. 156—42)

The invention relates to awnings and includes a window frame having an awning in combination therewith. More particularly, the invention relates to an awning so constructed as to lie entirely within a window frame when in inoperative position.

Awnings are extensively used in both residential buildings and industrial establishments. It is customary practice to hang the awnings by means of hooks positioned at convenient points in the upper portion of a window sash, such hooks being connectable to a rod usually carried by a hem forming the upper extremity of the awning. A U-shaped rod is provided in the lower portion of the awning in order to spread the same when in operative position and this U-shaped rod is either fixedly or movably pivoted to the window frame. Awnings of such conventional construction effectively shade the window when in use but, when in inoperative position, do not fit snugly within or even tight against a window frame with resultant loss in appearance to the building as well as frequent damage to the awning. Fires frequently occur, particularly in office buildings, and rain water accumulates in the pockets formed in the awning material.

The conventional awning has the further defect of preventing the utilization of shutters on windows so shaded. In areas where severe storms are prevalent, shutters are deemed to be essential in order to avoid damage to the windows. Moreover, shutters are desired on many residential buildings, principally for theiresthetic effect, and yet their utility is lost when they are used on a window having an awning of the usual type.

The present invention is designed to overcome the defects above referred to.

Accordingly, it is an object of the invention to provide an awning adapted to lie wholly within a window frame when in inoperative position.

A further object of the invention is to provide an awning enabling the utilization of shutters on the same window.

The invention includes as an object in combination a window frame provided with both an awning and shutters.

Further objects of the invention will appear in detail in the following description, as, for example, means to effect the folding of the aprons of an awning.

The invention is illustrated in the accompanying drawings wherein,

Fig. 1 is a perspective view of a window frame with the improved awning applied thereto.

Fig. 2 shows in elevation the awning in closed position.

Fig. 3 is a section taken on the line 3—3 of Fig. 2.

Fig. 4 illustrates the awning in open position, showing means for folding the apron.

Fig. 5 shows a modified form of the awning in which the material is self folding.

Fig. 6 is a view of the rear of an awning with means to pull in the side portions thereof.

Fig. 7 shows an alternative means for drawing in the apron.

In the drawings, A represents the wall of a building having a window frame 1 comprising a sill 2, a header 3, and side portions 4, 4. The side portions 4, 4 are provided with a bead 5, for holding the sashes 6, all as is well known in building construction. The sashes as shown are positioned with the normally upper sash lowered so as to simplify the illustration. Shutters 7, of the usual type, may be secured to the frame 1 by means of hinges 8.

My improved awning is generally designated by the numeral 9, composed of fabric material customarily employed in the art, and preferably though not necessarily provided with side portions 10 and an apron 11. The upper portion of the awning is permanently or detachably fastened to the upper strip of beading of the window frame and, in either case, the attachment is so effected that the upper extremity of the awning lies wholly within the limits of the frame.

For positioning the awning when in lowered position I provide a generally U-shaped rod 13 of the nature of the rods now known in the art. The rod 13 is, however, so designed with relation to the window frame as to lie wholly within the beading when in raised position. This is accomplished by making the foremost portion of the rod to be of a length appreciably less than the distance spacing the vertical beads 5. The side portions of the rod may be parallel to each other and therefore at right angles to the foremost portion, for a major portion of their length. Near the inner extremities of the rods 14, offsets or elbows 15 are provided, ending in heads 16 which may be secured to the beading by suitable means such as screws 17. It will be seen that this construction enables the rods, when in raised position, to lie wholly within the frame and in spaced relation to the frame to allow for the folds. The rods may be carried in a hem

in the awning material in the manner usual in the art.

Accordingly, it will be seen that the construction above described permits the awning to hang in a pleasing and effective manner when in use and to be housed within the limits of the window frame when in inoperative position.

In most awnings an apron will be employed and the apron usually overhangs by several inches the main portion of the awning defined by the rods. Such aprons do not ordinarily fold compactly and I have provided means to effect proper folding and avoidance of bulking of the material. Such means comprises a stay 18 contacting with the apron throughout a substantial portion of the length of the apron. The stay is secured to the apron at convenient points such as shown at 19, Figs. 2 and 4. The main portion of the stay 18 is spaced from the rod 14' and hinged connected thereto as at points 20, 20, the connection being such as to permit of at least partial rotation of the stay about the rod 14. Ordinary screw eyes serve well for such hinges. The rearmost portion of the stay 18 is offset at a point rearward of the corresponding hinge and terminates in an arm 21. The arm 21 in turn is bent right angularly so as to enter an eye 22 maintained in fixed position. In the frame illustrated the extending portion of the arm 21 where it is bent at an angle for passing through the eye 22, is disposed in an angle slightly in excess of a right angle and the free end is also disposed so that it extends slightly upward from the horizontal when viewed with the parts in the position assumed when the awning with its apron is extended. The eye 22 may conveniently be the extremity of an elbow 23 secured to the beading 5 by means of screws 24. This arrangement is such that the eye with the angularly disposed arm portion passing therethrough produces a cam action whereby the awning is raised thereby causing the extension of the stay 18 to pivot about the eye 22 and thus effect partial rotation of the stay 18 about the rod 14. The apron, being secured to the stay, is thus folded inwardly of the rod 14.

Alternatively, a modified form of means for retracting the apron is shown in Fig. 7. In this form a cord or like flexible element 25 is secured at an extremity 26 to a portion of the apron and movably attached thereto at other points 27. The cord 25 is likewise movably attached to portions of the side walls above the rod, as at 28, and ultimately passed through a loop 29 preferably mounted on the bead 5. Upon tensioning the cord 25, the apron will be drawn in to a corresponding degree.

I preferably crease the awning material along the lines of fold as in the manner shown in Fig. 5 so that, when raised, the material will inherently fold in a compact manner and readily assume the position illustrated in Figs. 2 and 3. The awning 9 shown in Fig. 5 is preferably composed of a fabric material having a main section 9a and side sections 9b joined together by lines of stitching. An apron 11a extends along substantially the entire lower edge of the sections 9a and 9b, the apron similarly being joined by a line of stitching to the lower edge of the respective sections. The material of the awning is creased along the seams, or when the awning is made of one piece of material, along the lines indicated in the drawings as dividing the sections 9a and 9b and the apron 11a, and the manner of creasing causes the material to tend

to fold as illustrated while the awning is being elevated to its closed position. The pull-up cord 12a for elevating the awning is divided at its lower end to form extensions 12b, which extensions are connected to the apron 11a at the points on the side walls thereof as indicated at 11b. The cord or rope 12a passes through an opening 9c formed in the section 9a and passes through another opening 9d formed in said section, to the interior thereof. When the awning is in position for use the pull cord extends through an eyelet or pulley at the top of the window frame with its end extending downwardly for the convenience of the operator. It will be seen that when the awning as shown in Fig. 5 is to be raised to a closed position, the operator by drawing on the inner end of the pull-cord will cause the apron to be first folded inwardly and thereafter the pull will be applied to draw the lower outer part of the awning upwardly. Due to the creased lines of fold the awning sections will tend to fold as illustrated and the further closing of the awning will result in the same assuming a compact formation.

In some cases it will be desirable to provide positive means for drawing the side walls inwardly during the raising of the awning. Means for accomplishing this result is shown in Fig. 6. In this, a cord 30 is stretched between the two side walls and attached thereto as at 31, 31. By simply depressing the cord, the side walls will be drawn toward each other and so tend to fold toward the inner portion of the awning.

Conventional means may be employed to raise the awning. However, due to the lightness of the construction, a single cord centrally positioned will ordinarily be sufficient for the purpose. A cleat 32 is provided for securing the cord and maintaining the awning in raised position.

With the awning above described and illustrated, it will be seen that all the desired utility for shading is preserved and likewise that the awning is entirely disposed within the window frame when not in use. Thus interference with the operation of shutters is entirely avoided and so the occupant of the building is enabled to obtain the benefits of both elements.

While the invention has been described in specific form for purposes of illustration I do not confine myself to the details of the invention except according to the following claims. It will also be apparent that the awning may be used in conjunction with a door frame and the term "frame" appearing in the claims is used generically.

I claim:

1. An awning for use in conjunction with a frame comprising a sheet of fabric material secured along one edge to the frame and a pivoted rod, said rod being secured to the fabric adjacent the free edge thereof and holding the sheet in extended position when the rod is swung outwardly, said awning including side walls, an apron arranged along and extending from the lower portion of the sheet and below the rod, a stay fastened to said apron having an offset portion rotatably connected to said rod, and means for effecting a rotation of said stay and a resultant movement of the apron when the rod is pivoted upwardly in the raising of the awning whereby the apron will lie compactly folded against the remainder of the awning.

2. An awning for use in conjunction with a

frame comprising a sheet of fabric material secured along one edge to the frame and a pivoted rod, said rod being secured to the fabric adjacent the free edge thereof and holding the sheet in extended position when the rod is swung outwardly, said awning including side walls, an apron arranged along and extending from the lower portion of the sheet and below the rod, a stay fastened to said apron having an offset

portion rotatably connected to said rod, and cam mechanism for effecting a rotation of said stay and a resultant movement of the apron when the rod is pivoted upwardly in the raising of the awning whereby the apron will lie compactly folded against the remainder of the awning.
